UNITED STATES PATENT OFFICE.

JAMES M. COLEMAN, OF WESTMOUNT, QUEBEC, CANADA, ASSIGNOR OF ONE-HALF TO
KARL F. NYSTROM, OF ST. LAMBERTS, MONTREAL, QUEBEC, CANADA.

REFRIGERATOR-CAR.

1,305,772.

Specification of Letters Patent. Patented June 3, 1919.

Application filed September 30, 1916. Serial No. 122,970.

To all whom it may concern:

Be it known that I, JAMES M. COLEMAN, a citizen of the United States, residing at Westmount, in the Province of Quebec and 5 Dominion of Canada, have invented a certain new and useful Improvement in Refrigerator-Cars, of which the following is a full, clear, concise, and exact description, reference being had to the accompanying 10 drawings, forming a part of this specification.

This invention relates to improvements in refrigerator cars.

One object of the invention is to provide 15 an improved type of refrigerator car having a collapsible ice box so adapted as to provide a maximum radiating surface when in extended position with the ice therein, and at the same time arranged to be collapsed 20 so as to occupy a minimum amount of space in the car when icing of the car is not desired.

Another object of the invention is to provide 25 a refrigerator car having a more efficient arrangement for keeping the interior temperature lowered than has hitherto been employed.

The invention furthermore consists in the 30 improvements in the parts and devices and in the novel combination of the parts and devices herein shown, described and claimed.

In the drawing forming a part of this 35 specification, Figure 1 is a vertical, transverse sectional view of a refrigerator car near one end thereof and showing the improvements in connection therewith. Fig. 2 is a longitudinal, vertical sectional view taken substantially on the line 2—2 of Fig. 1, showing the ice box arranged to receive 40 the ice. Fig. 3 is a view similar to Fig. 2, but illustrating the position of the parts when the ice box is in collapsed condition. Fig. 4 is a horizontal sectional view taken 45 substantially on the line 4—4 of Fig. 1. Fig. 5 is a detailed sectional view taken substantially on the line 5—5 of Fig. 2. Fig. 6 is another detailed sectional view, taken substantially on the line 6—6 of Fig. 7. Fig. 7 is an enlarged, vertical, longitudinal sectional view, similar to Fig. 2, but showing more in detail the arrangement 50 of the ventilator and the hatches, parts being broken away in order to prevent crowding of the drawing. Fig. 8 is a view simi-

lar to Fig. 4, at one end of the ice box, but showing the position of the parts when the ice box is in collapsed condition. Fig. 9 is a detail, side elevation of a portion of the car roof and showing more particularly 60 one of the hatches and the operating mechanism for the ventilators. And Fig. 10 is an enlarged, horizontal sectional view taken substantially on the line 10—10 of Fig. 9. 65

In said drawing, 10—10 denote the insulated side walls of the car, 11 the insulated end wall, 12 the roof of the car, and 13 the floor thereof. In the roof of the car are provided two hatches, 14, 14, each of 70 the same being adapted to be closed by an insulated door 15 having compressible packing around its edges, and a hinged outer trap door 16. As clearly appears from Fig. 1, both of said hatches are disposed above 75 the ice box so that ice may be readily introduced into the latter from either side of the car. In the end wall 11 of the car, near the upper portion thereof, is provided an air inlet 17, which communicates with a 80 downwardly extending vertical air duct 18 (see Figs. 2 and 7), said air duct 18 communicating in turn with an air space 19, which extends across the car and is formed between the inner face of the end wall of 85 the car and the rear or back wall of the ice box proper, hereinafter more particularly described.

To regulate the amount of air permitted 90 to pass into the car, I have provided the following novel arrangement. To prevent the admission of dirt, dust or other foreign matter, I provide a screen 25 over the entrance, as clearly indicated in Fig. 7. On the outer side of the screen is provided 95 a hinged sheet metal shutter 20, the same being mounted on a transversely extending rod or shaft 136 having its ends mounted in suitable bearings 137—137, one end of said rod or shaft 136 being extended outside of the hatch for the purpose herein-after described. On the inner side of the screen 25 and closely adjacent thereto, is a second shutter 21 which is in the form of a triangular shaped wooden strip. This 100 wooden strip is preferably incased in canvas on all sides and a metal sheeting 140 is provided on the two sides which are normally vertical and at an acute angle to the vertical. Said shutter 21 is mounted on 110

suitable short shafts 141 at the ends thereof, the latter being mounted in similar bearings 137-137, one of said shafts being extended outside of the hatch, for the purpose hereinafter described. In order to form a tight closure at the entrance to the air passage when the shutters are closed, I provide a suitable spring pressed packing 24 that co-operates with the shutter or valve 21. As clearly shown in Fig. 7, when the shutter 21 is in closed position a tight joint is made between the lower face thereof and said yieldable insulating packing.

Referring now more particularly to Figs. 9 and 10, it will be seen that the extended end of the shaft or rod 136 and the adjacent short shaft 141 are provided with squared ends 146 and mounted on said squared ends are levers 147 and 148, the same being pivotally connected as by links 149. The lever 148 has preferably formed integrally therewith an operating handle 150 which slides within a suitable keeper 151, the latter being provided with a series of pin-receiving perforations 152 by which the handle 150 may be locked in different adjusted positions.

From the preceding description, considered in connection with the drawing, it will be seen that by manipulating the handle 150, the two shutters 20 and 21 are simultaneously operated and always in opposite directions. By this means the amount of air admitted can be regulated as desired or entirely shut off, and a substantially complete insulation obtained.

The ice box proper is preferably of rectangular form when in open or extended condition, as clearly appears from Fig. 4. As shown, the same comprises a rear wall 26 of sheet metal corrugated vertically, said sheet metal wall 26 being braced and held in proper position relatively to the end wall of the car by vertical posts 27, 28, 29 and 30. Said posts are supported on the floor of the car, and extends almost to the top thereof, and are of such width as to snugly fit within the corrugations of the sheet metal wall 26. Each of the side walls 31, 31, of the ice box also consists of a sheet of metal corrugated vertically, said sheet metal walls being secured to a plurality of vertically extending studs 32, 32, which also fit within the corrugations of the sheet metal. The studs 32 and sheet metal wall, at each side of the ice box, are pivoted as a unit about a vertical axis, as indicated at 33. Each side wall, thus formed, is adapted to be swung to a position parallel with the end wall of the car and as clearly indicated in Fig. 8. The bottom of the ice box, which is elevated above the floor of the car, consists of four sections A, A, A, A, each section A comprising a plurality of longitudinally extending, spaced, parallel slats 34, suitably united

at their ends by blocks 35 and a through bolt 36. Each of said sections A is pivoted along the edge adjacent the wall 26 of the ice box, as indicated at 37. The inner ends of the sections A are supported, when in horizontal position, by suitable brackets 38 mounted on blocks 39 (see Figs. 2 and 3). The sections A are adapted to be swung upwardly to a vertical position against the wall 36, this position being clearly shown in Fig. 8, the side walls being swung inwardly after the sections A have been swung upwardly. The sections A are supported at their outer free ends, when in horizontal position, on a transversely extending joist 40, which forms part of a framework for the front or inner wall 41 of the ice box.

Said framework includes said joist 40, vertical end posts 42, 42, intermediate bracing posts 43, 43 which fit in the vertical corrugations of the sheet metal wall 41, and a horizontally extending bottom member 44, all of said parts being suitably bolted or otherwise secured together. The framework and the inner wall 41 itself are retained in the position shown in Fig. 4 by any suitable means, such as the horizontal slidable bolts 45, slidably mounted in brackets 46, said bolts 45 being adapted to be pushed into suitable sockets 47, 47, in the side walls of the car. After the bottom sections A have been swung to vertical position, and the side walls swung inwardly parallel with the end wall of the car, the inner or front wall 41 of the ice box may then be moved toward the end of the car to the position indicated in Fig. 8. To do this, the bolts 45 are withdrawn from their corresponding sockets, and said wall 41 pushed rearwardly. As clearly appears from Figs. 1, 2 and 3, the end vertical posts 42, 42 are provided with upwardly extending brackets 48, 48, which carry rollers 49, 49, said rollers riding on tracks 50, secured to the side walls of the car. Each track 50, at the end farthest removed from the end wall of the car, is provided with a depression 51 into which the rollers 49 drop when the inner wall 41 is farthest away from the end wall of the car.

As the front wall 41 is started toward the end wall of the car, the rollers 49 ride up to the horizontal portion of the track 50 and thereby support the frame work and end wall 41 slightly above the floor. At their inner ends, the tracks 50 are provided with upwardly extending curved portions 52, which limit the inward movement of the rollers 49. When the end wall is moved as near the end wall of the car as possible, as shown in Figs. 3 and 8, the bolts 45 are then pushed outwardly into other suitable sockets 53 in the side walls of the car. In this manner, the wall 41 is not only held in position, but also the side walls and sections A of the ice box bottom. As will be

70

80

85

90

100

110

120

130

noted in Figs. 1, 3 and 7, the front and rear walls 41 and 26 of the ice box do not extend up to the roof of the car, but terminate a sufficient distance below the roof to permit part of the incoming air to circulate over the top of the ice box.

From the preceding description, it will be seen that I have provided an ice box having a relatively large radiating area, the box being open on all sides, and so arranged that the incoming air strikes the walls of the ice box directly, and the air is thereby thoroughly chilled before it passes under the ice box and to the main portion of the car. The ice box, when opened up or extended, is of comparatively large capacity, but when collapsed occupies a minimum amount of space, thereby increasing the capacity of the car when the same is not used for refrigerating purposes. The walls being of sheet metal may be cheaply and easily manufactured, with the corrugations therein; the corrugations extending vertically provide great strength in said walls against lateral and longitudinal stresses; and the corrugations coöperate in reducing the volume of space required for the frame work of the ice box, inasmuch as the wooden posts or joists may be fitted within the corrugations, as hereinbefore described.

Although the preferred embodiment of the invention has been herein illustrated and

described, the same is merely illustrative, and all changes and modifications are contemplated as come within the scope of the 35 claim appended hereto.

I claim:

In a refrigerator car, a collapsible ice box, said ice box having a back wall formed of corrugated sheet metal and spaced from the 40 inner face of the end wall of the car to thereby provide a vertical air passage, said box having also side and front walls formed of corrugated sheet metal, the side walls being spaced from the inner faces of the 45 side walls of the car to also provide vertical air passages, studding located at spaced intervals on the outer sides of said side walls and attached thereto, said side walls of the box being movable to a position paralleling the end wall of the car when the ice box is collapsed, said front wall of the box being also shiftable back and forth and relatively to said rear wall of the box, and means for holding said front wall in either its extended or retracted position.

In witness that I claim the foregoing I have hereunto subscribed my name this 5th day of Sept., 1916.

JAMES M. COLEMAN.
